[57] **CLAIM**

The ornamental design for a dental accessory cabinet, as shown and described.

DESCRIPTION

FIG. 1 is a perspective front elevation;

FIG. 2 is a perspective rear elevation with the top portion hinged away from the main body;

FIG. 3 is a rear elevation;

FIG. 4 is a left hand side elevation, the right hand side elevation being substantially a mirror image; and

FIG. 5 is a plan view.

Details of the underview do not form any part of the present design. The cylindrical surface may carry gauges and switches (not shown) which do not form a part of the present design.
